END GRINDING OF BEARING ROLLERS

Theodore A. Olson, Pompton Plains, N. J., assignor to General Motors Corporation, Detroit, Mich., a corporation of Delaware

Application August 31, 1948, Serial No. 47,059

13 Claims. (Cl. 51—130)

1

This invention relates to the end grinding of bearing rollers and comprises all of the features of novelty herein disclosed. An object of the invention is to provide an improved machine for abrading the ends of anti-friction bearing rollers. Another object is to provide an improved machine for grinding spherical ends on tapered rollers in a continuous operation. To these ends and also to improve generally upon machines of this character, the invention consists in the various matters hereinafter described and claimed.

In the drawings, Fig. 1 is chiefly a vertical section of the machine on line 1—1 of Fig. 2.

Fig. 2 is a plan view of important elements of Fig. 1.

Fig. 3 is a side view of a loading block and its support.

Fig. 4 is a plan view of an ejecting device.

Fig. 5 is a front view of Fig. 4.

Fig. 6 is a plan view of a ring.

Fig. 7 is a sectional view on line 7—7 of Fig. 6.

First outlining the operation, tapered rollers are ground at their ends by a grinding wheel having a spherical zone. The rollers are rotated on their axes many times while travelling bodily in a circular channel formed between two oppositely rotating members which have conical work engaging surfaces one outside of the other. The conical surfaces position the rollers so that their axes always point to a common point which is the apex of the included angle and that apex is the center of curvature of the abrasive surface. The wheel axis is offset or inclined so that a portion of the channel is exposed for insertion and removal of the rollers in a continuous operation.

The base plate 2 is rectangular and has an upstanding rim formed by angle irons 4 fastened thereto. A support is fastened to the base plate and is made up of welded sections comprising spaced feet 6 with side walls 8, the latter being connected by a vertical cross web 10. Welded on top of these members is a square plate 12 having a round opening for a fixed supporting housing 14. The housing has a flange 16 connected to the plate by screws and it is counterbored to receive a pair of bearing bushings 18 whose outer ends have slots 20, preferably six each, and whose bores have longitudinal slots 22, preferably three each, all for the passage of air loaded with an oil mist introduced through a radial hole 24 having a pipe tap.

Journalled for rotation in the bushings is a hollow shaft or sleeve 26 having a flange resting on the upper bushing and provided with a circular shield 28 overlapping the upper end of the hous-

2

ing. The sleeve 26 has an external groove 29 opposite the opening 24 and radial holes extend from the groove through the sleeve to direct the lubricant to bearing bushings 30 and 32 and to ball thrust bearing 34. The upper bushing 30 is similar to the bushings 18 but the lower bushing 32 lacks slots at the lower end which engages the upper thrust washer of the ball thrust bearing. A second hollow shaft or sleeve 36 is journalled for rotation in the bushings 30 and 32 and its upper end has a flange resting on the upper bushing. The lower end of the sleeve 26 has a driving pulley 38 and the lower end of the shaft 36 has a driving pulley 40, these pulleys driving the sleeves in opposite directions at slightly different speeds from a suitable source.

Fastened by screws to the upper end of the shaft 36 with a spacer 42 interposed between is an externally circular member, which may be a ring, but is herein shown as a disc 44 having a conical periphery and an upper surface which is a segment of a sphere or otherwise shaped to conform closely to the surface of a grinding wheel G which is driven on an inclined axis. The disc carries a diamond 46 to keep the wheel dressed. The lower side of the disc has an annular groove receiving the upper end of a circular shield 48 which is pressed within a little upstanding flange on the sleeve 26. The sleeve has three vertical holes 50 each hole intersecting a short horizontal hole and these holes direct spent lubricating atmosphere through three horizontal grooves 52 in the bottom of a ring 54 which is secured by screws to the sleeve 26.

The ring 54 has an interior conical face to engage the tapered rollers R in opposition to and surrounding the conical face on the disc 44, these conical faces making the same angle with one another as the included angle of the rollers and the apex of the cones intersecting at a common point where the apex of the rollers would meet if produced. To discharge grit the ring 54 has a series of horizontally elongated slots 56 which slant downwardly through it from the annular space below the rollers. The conical faces of the disc and the ring are spaced apart to form a circular channel for guiding tapered rollers sideways in an arcuate path. The rollers naturally locate themselves with their axes pointing to a common center at the apex of the conical surfaces.

Since the grinding wheel axis is inclined or offset out of alignment with the common axes of the disc 44 and the ring 54, a portion of the circular channel between the conical work engaging

surfaces is exposed for insertion and removal of the rollers. The rollers are delivered small end first from a flexible feed tube 60 into a hollow loading block 62 having an inclined bore. The block is secured by screws to a slanting surface on a bracket 64 whose base is fixed to the top of the plate 12. After rotating on their axes many times and traveling bodily around the channel between the oppositely rotating conical surfaces for the greater part of a revolution, the tapered rollers are expelled by a cam surface 66 on an ejecting finger 68. This finger projects downwardly between the conical faces and laterally in a curve to lie in the path of and engage the small end of each ground roller which rides up the cam surface and is discharged. The finger has a slotted upper portion 70 which is adjustably secured by screws to a slanting surface on a bracket 12 fastened on the top of the plate 12.

The grinding wheel G comprises a ring of abrasive whose lower surface is the zone of a sphere when the ends of the rollers are to be made spherical. The wheel is secured to a plate 74 which is secured to a conventional grinding spindle mounted for rotation in a quill 76 set at an angle to the vertical and adjustable to feed the grinding spindle longitudinally of its axis. The axis of the spindle is arranged to intersect the apex of the conical surfaces and this apex is the center of curvature of the spherical zone of the grinding wheel. The grinding wheel is driven at usual grinding speed. Suitable speed of rotation of the disc 44 is 100 R. P. M. clockwise, and for the ring 54 it is 96 R. P. M. counterclockwise. This differential will cause bodily travel of the rollers in an arcuate path at a bodily speed of 2 R. P. M. but the rollers being of relatively small diameter will rotate on their axes many times between their points of insertion and removal. For rollers of different dimensions, the disc 44 and the ring 54 are readily replaced by other suitably dimensioned ones.

I claim:

1. In a machine of the character indicated, a disc having a peripheral work engaging surface, a ring having an interior surface surrounding the first surface and forming a circular channel therewith for guiding elongated articles sidewise, means for rotating the disc in one direction, means for rotating the ring in the opposite direction at a different speed, a rotary abrasive wheel having its axis out of alignment with the axes of the disc and the ring to leave a portion of the channel exposed, means for introducing articles endwise into the channel at the exposed portion, and means for removing end-ground articles at an adjacent point after travel along the abrasive wheel.

2. In a machine of the character indicated, a disc having a conical work engaging surface, a ring having a cooperating conical surface surrounding the first conical surface and forming therewith a circular path of travel for tapered rollers, means for rotating the disc in one direction, means for rotating the ring in the opposite direction at a different speed, a wheel having a concave abrasive surface, means for rotating the wheel around an axis lying at an acute angle to the common axes of the disc and the ring to leave a small portion of the circular path exposed, means for introducing tapered rollers endwise into the path at the exposed portion, and means for removing end ground rollers at an adjacent point after travel along the abrasive wheel.

3. In a machine of the character indicated, a

disc having a conical work engaging surface, a ring having a cooperating conical surface surrounding the first conical surface to form therewith a circular channel for grinding tapered rollers, means for rotating the disc and the ring in opposite directions at different speeds, a rotary wheel having an annular abrasive surface and an axis of rotation out of alignment with the axes of the disc and the ring to leave a small portion of the channel exposed and to cover the greater portion, means for introducing tapered rollers endwise into the channel at the exposed portion, and means for removing end-ground rollers at an adjacent point of the channel.

4. In a machine of the character indicated, a disc having a peripheral work engaging surface, a rotary ring having an interior surface surrounding the first surface and forming a circular channel therewith for guiding elongated articles sidewise, means for rotating the disc in one direction, means for rotating the ring in the opposite direction at a different speed, and a rotary wheel having an abrasive surface to engage projecting ends of the articles as they progress sidewise in the channel, said wheel being driven and having its axis inclined at an angle to the axis of the rotary ring to expose a portion of the circular channel.

5. In a machine of the character indicated, a disc having a peripheral work engaging surface, a rotary ring having an interior surface surrounding the first surface and forming a circular channel therewith for guiding elongated articles sidewise, means for rotating the disc in one direction, means for rotating the ring in the opposite direction at a different speed, and a rotatably driven concave abrading surface engaging the projecting ends of the articles as they progress sidewise in the circular channel, said abrasive surface being a spherical zone and having its axis tilted with respect to the axis of the rotary ring.

6. In a machine of the character indicated, a disc having a conical work engaging surface, a rotary ring having an interior conical surface surrounding the first surface and forming a circular channel therewith for guiding conical rollers sidewise, means for rotating the disc and the ring in opposite directions at slightly different speeds, a rotary wheel having a spherical abrasive surface engaging the projecting ends of the rollers, and the axis of rotation of the wheel being placed at an angle to the axes of the disc and the ring to leave a portion of the channel uncovered.

7. In a machine of the character indicated, a disc having a conical work engaging surface, a rotary ring having an interior conical surface surrounding the first surface and spaced therefrom to form a circular channel for guiding conical rollers, means for journaling the ring for rotation, means for rotatably driving the ring to cause the rollers to rotate and progress circumferentially in the channel, and a rotary wheel having an abrasive surface covering the greater portion of the circular channel for abrading the ends of conical rollers inserted and removed at the uncovered portion of the channel in a continuous operation.

8. In a machine of the character indicated, a disc having a peripheral work engaging surface, a rotary circular ring having an interior surface entirely surrounding the first surface and forming a circular channel therewith for guiding elongated articles sidewise, the opposed surfaces of the disc and the ring being conical with a com-

mon apex in the common axis of the disc and the ring, the wider side of the circular channel facing upwardly, a rotary abrasive wheel having its axis out of alignment with the axis of the disc to leave a portion of the channel exposed, a feed tube directed downwardly towards the apex of the conical surfaces for introducing articles endwise one at a time into the channel at the exposed portion, and a member projecting into the channel from the wider side thereof at the exposed portion and having a cam surface extending into the path of ground articles to remove them upwardly and endwise from the channel.

9. In a machine of the character indicated, a disc having a conical work engaging surface, a ring having an interior conical surface surrounding the first surface and forming a circular channel therewith for guiding tapered rollers sidewise, means for rotating the disc in one direction, means for rotating the ring in the opposite direction at a different speed, a rotary abrasive wheel engaging the ends of the rollers and having its axis out of alignment with the axes of the disc and the ring to leave a portion of the channel exposed, means for introducing rollers small end foremost into the channel at the exposed portion, and a member having a cam surface to engage the small ends of ground rollers as they approach the exposed portion for removing the rollers from the channel.

10. In a machine of the character indicated, a disc having a peripheral work engaging surface, a ring having an interior surface surrounding the first surface and forming a circular channel therewith to guide elongated articles sidewise, means for rotating the disc, a rotary wheel having an annular abrasive surface to engage the ends of the articles projecting from the channel, the axis of rotation of the wheel being offset from the axis of the disc to cause a relative wiping action between the abrasive surface and the ends of the articles, and a wheel dressing diamond carried by the disc at a point near the channel.

11. In a machine of the character indicated, a disc having a conical work engaging surface, a rotary ring having an interior conical surface surrounding the first surface and forming a circular channel therewith, means for rotating the disc and the ring, a rotary wheel having an abrasive surface of spherical form to engage the ends of

articles projecting from the channel, the axis of the wheel being inclined to the axis of the disc, and a wheel dressing diamond carried by one of the rotary members which form the channel.

- 5 12. In a machine of the character indicated, a support, a hollow shaft journalled for rotation in the support, an inner shaft journalled for rotation in the hollow shaft, means for rotating said shafts, a member fixed to one end of the inner shaft and having a peripheral work engaging surface, a ring fixed to one end of the hollow shaft and having an interior work engaging surface surrounding the first surface to form a circular work guiding channel therewith, an abrasive member for operating on the projecting ends of articles in the channel, and the ring having radial openings extending therethrough from one end of its interior surface to discharge grit.
- 15 13. In a machine of the character indicated, a support, a hollow shaft journalled for rotation in the support, an inner shaft journalled for rotation in the hollow shaft, means for rotating said shafts, a member fixed to one end of the inner shaft and having a peripheral work engaging surface, a ring fixed to one end of the hollow shaft and having an interior work engaging surface surrounding the first surface to form a circular work guiding channel therewith, an abrasive member for operating on the projecting ends of articles in the channel, the ring having radial openings extending therethrough from one end of its interior surface to discharge grit, and a circular shield between the ring and said member.
- 20 30
